UNITED STATES PATENT OFFICE.

WILLIAM D. CRITES, OF DULUTH, MINNESOTA.

GAS BURNER.

Application filed July 18, 1924. Serial No. 726,738.

To all whom it may concern:

Be it known that I, WILLIAM D. CRITES, a citizen of the United States, residing at Duluth, in the county of St. Louis and State 5 of Minnesota, have invented certain new and useful Improvements in Gas Burners, of which the following is a specification, reference being had therein to the accompanying drawing.

10 This invention relates to gas burners and has special reference to a burner used within a furnace such as employed in house heating, or the like.

The principal object of the invention is 15 to provide a novel form of burner which will produce the greatest amount of heat possible in proportion to the fuel consumed.

Another object is to produce such a burner 20 particularly adapted for convenient installation to an ordinary furnace.

Still another object is to provide novel 25 means associated with the burner for retaining heat and diffusing it as nearly as possible within the combustion chamber of the burner.

Other objects and advantages of the invention will appear in the further description thereof.

Referring now to the accompanying drawing, forming part of this application, and 30 in which like reference characters indicate like parts:

Figure 1 is an elevation, partly in section and partly broken away, of one of my improved burners.

Figure 2 is a horizontal section taken on the line 2—2, Figure 1; and

Figure 3 is a section taken on the line 3—3, Figure 1.

40 The grate of the furnace, the construction of which is not material to the invention, is illustrated at 1, through which is installed the vertically disposed gas supply pipe 2, it being shown as connected below the grate 45 1 to a horizontal pipe 3 having installed therein the usual gas and air mixing valve 4 which is manually manipulated in the usual manner externally of the furnace walls.

50 The pipe 2 forms an axial support for the separable burner housing comprising the four parts 5, 6, 7, and 8, the lower body portion 5 of which is mounted upon the circular collar or ring like plate 9 which rests upon the top of the grate. The plate 55 9 is provided centrally with an upstanding

annular ring 10 about which the lower body portion 5 of the burner housing rests, and the top wall or plate 6 of the lower portion of the housing is snugly fitted therupon 60 by having a depending flange 11 formed integral therewith which surrounds the upper end of the lower body portion 5, said plate having an axial hole to snugly fit the pipe 2, and also a plurality of radially disposed 65 ports or openings 12 therein.

The intermediate body portion is cylindrical in form and of the same size in diameter as the lower body portion, it having a bottom plate 13 formed integral therewith, 70 having holes 14 formed therein similar to the holes 12, and which register therewith when the intermediate body portion is rotated for such purpose; there being a radially extending handle 15 for such purpose. 75 These ports are for the purpose of regulating the supply of air passing upwardly through the body portion of the burner. The plate 13 of the intermediate portion 7 is provided with a central axial hole which snugly fits 80 about the pipe 2 forming a pivotal mounting for same so that the rotative adjustment of the upper portion of the burner may be readily accomplished.

Carried upon the intermediate portion 7 85 is the crown 8 of the burner housing, there being a plurality of narrow spaces or slots 16 intermediate of the intermediate portion 7 and the crown for the discharge of gas or flame, as the case may be. The upper portion 90 of the crown is flared outwardly so as to extend somewhat beyond the body portion and has formed through the upper circumferential wall thereof a plurality of quite large holes 23 for distribution of the flame 95 or gas, and the entire flat top of the crown 8 is provided with any desired number of small holes or discharge orifices 17 for a like purpose.

The nozzle 18 attached to the upper end 100 of the pipe 2 is also provided with a plurality of slots 19 in the upper flaring circumferential portion thereof for the discharge of gas therefrom.

The body portion of the burner is surrounded within the fire box of the furnace by any desired heat retaining substance such for example as sand and broken bricks or other like material, and the preferred arrangement of this is illustrated as the 110 sand 20 occurring first upon the grate which may be covered with heavy paper, canvas,

or other such material to prevent the sand falling through, and then surmounted with the crushed stone or brick, as illustrated at 21. In this manner means for retaining 5 heat produced by the burner is provided with the least expense possible, and the burner as disclosed has proven very efficient in heat production in that combustion first takes place about the nozzle 18 within the 10 uppermost portion of the burner, and the unburned gases thus produced being confined within the superheated body portion of the burner will discharge through the crown of the same, and further ignited, in- 15 tensifying the heat and materially improving the efficiency of the burner.

Within the ring 9 and spaced some little distance from the side walls of the body portion of the burner are upright pipes or 20 tubes 22, they being open at both ends forming communication intermediate of the space above the heat holding aggregate and below same so that additional air is allowed to circulate therethrough in providing 25 oxygen for the combustion taking place externally of the burner, and there may be any number of these pipes as desired, preferably four or more.

Having thus described my invention, 30 what I claim and desire to secure by Letters Patent, is:

1. A gas burner of the type described comprising an upright three-part rotatably adjustable cylinder having an axial gas 35 burner therein, portions of said cylinder being adjustable about the burner as an axis to regulate the air passing through the cylinder to the burner, the upper portion

of said cylinder being outwardly flared and provided with discharge ports, some of said 40 ports occurring below the flared portion and some above the flared portion.

2. The combination with a furnace having a fuel grate therein, of a gas burner within the furnace supported upon the 45 grate comprising a rotatably adjustable upright cylinder, a gas supply pipe disposed axially of the cylinder and terminating within the upper portion thereof, one section adjustably supported upon the other, means for regulating the circulation of air through the cylinder, granular material surrounding the cylinder, resting upon the grate, and graduated upwardly from fine 50 to coarser, and a plurality of upright pipes 55 installed within the granular material and spaced from the gas burner to supply additional air therefor.

3. A gas burner of the type described comprising an upright hollow cylinder, a covering member for said cylinder having ports therethrough, a second cylinder mounted directly upon the cover of the first mentioned cylinder and having ports 60 therein for optional registration with the ports in said cover, a perforated crown mounted directly upon the second cylinder, and an upright burner within 65 said cylinder forming an axial support therefor, the terminal of said burner occurring within the uppermost cylinder and beneath the crown.

In testimony whereof I hereunto affix my signature.

WILLIAM D. CRITES.
